ARTICHOKE DISH

William S. Corey, 10236 Mount Gleason,
Tujunga, Calif.

Filed Sept. 4, 1962, Ser. No. 71,530

Term of patent 14 years

(Cl. D44—15)

FIG. 1.

FIG. 4.

FIG. 2.

FIG. 3.

FIG. 5.

FIG. 1 is a perspective view of an artichoke dish showing my new design;

FIG. 2 is a top plan view;

FIG. 3 is a front elevational view;

FIG. 4 is a bottom plan view; and

FIG. 5 is a left side elevational view.

I claim:

The ornamental design for an artichoke dish, substantially as shown.
